BUCK FOR PRESSING MACHINES

George H. Rawlinson and Richard A. Rawlinson,
Portland, Oreg.

Application April 11, 1938, Serial No. 201,352

10 Claims. (Cl. 223—57)

This invention relates to a so-called buck or form on which garments, particularly shirts, coats and the like, are pressed in the garment pressing machine, and this application is a continuation in part of application, Serial No. 90,656, filed July 15, 1936.

The object of this invention is to provide an improved buck on which garments of varied sizes may be properly supported and pressed.

10 A more specific object of this invention is to provide an adjustable buck, by means of which the body portion of the garment will be smoothed and held firmly during the pressing operation.

Another particular object is to provide efficient, 15 practical adjustable means whereby those portions of the garment beneath the armholes will be properly held and stretched, and will be pressed simultaneously with the pressing of the rest of the garment body regardless of whether 20 the garment is form fitting (that is with the portions beneath the armholes curving inwardly), or is otherwise varied in shape or size.

Another object of this invention is to have the means for holding the side portions of the 25 garment constructed with sufficient flexibility and resiliency to make possible the stretching of these portions to the full extent but yieldingly to a certain extent, thus without danger of tearing or otherwise injuring the garment, or in any 30 way subjecting it to too great a strain.

A further object of this invention is to provide a simple and efficient means for holding the garment when in draped position on the buck.

A further object is to provide movable sleeve 35 supporting means for holding the sleeves spaced from the body of the garment and thus out of the way of the press elements during the pressing of the garment body.

A further object is to provide means for holding 40 the collar or neckband firmly in place on the buck and so to connect this holding means and arm supporting means that both means will be operated simultaneously thru the medium of a single control.

45 A still further object is to provide a surface covering for a buck of the type indicated which has sufficient resistance, resiliency and stability to produce most efficient results when the buck is used with pressing jaw elements.

50 The novel manner and means by which the above mentioned and incidental objects are attained, particularly the flexible adjustable and resilient means for stretching and holding the side portions of the garment properly extended 55 and positioned during the pressing operation,

are hereinafter fully described with reference to the accompanying drawings.

In the drawings:

Fig. 1 is a front elevation of our improved buck illustrating the various parts in position for holding and stretching a garment, the garment being shown in broken lines;

Fig. 2 is an end elevation of the buck corresponding to Fig. 1;

Fig. 3 is a transverse sectional view on the line 10 3—3 of Fig. 1, looking in the direction indicated by the arrows, the section, however, being drawn to a larger scale than Fig. 1 and parts being omitted for clarity;

Fig. 4 is a partial vertical section on the line 15 4—4 of Fig. 1 illustrating part of the operating mechanism, but also drawn to a larger scale;

Fig. 5 is a vertical medial section showing the garment supporting and stretching mechanism;

Fig. 6 is a fragmentary side elevation corresponding to the upper portion of Fig. 5; and

Fig. 7 is a fragmentary, more or less diagrammatic, vertical section through the buck, drawn on an enlarged scale, showing a garment on the buck and illustrating corresponding sections of 25 the pressing jaws in operative pressing position.

Referring first to Figs. 1, 2 and 3, the body of the buck consists preferably of a hollow casting or metal shell 10 substantially elliptical in cross-section but having flattened end sections as 30 shown in Fig. 3. The upper portion of the metal shell 10 is preferably shaped to resemble the shoulders and neck of a human torso, these parts of the buck being designated 11 and 12, respectively, in Figs. 1 and 2. Closely covering the 35 metal shell 10 and the neck portion 12 and conformably stretched thereon is a sheath 13, made of highly resilient material, such as rubber, and preferably molded in one piece, or split down the sides and fastened together there, so as to eliminate any seams or joints on the front and back of the buck. We have found it practical and efficient to make this sheath of highly resilient rubber about $\frac{1}{2}$ an inch in thickness, and to cover the same on the outside with a soft fabric 40 cover.

When the garment is draped on the buck and smoothly arranged to conform to the outer surface of the buck, the neck portion of the garment is clamped by means of a clamp device to 50 be described later, and the front flaps of the garment are brought into correct position and are held in this position by a flexible tape 14 which is formed of thin metal or other suitable flexible material. The ends of the flexible tape 55

14 are attached to upstanding rods 15, which rods are rigidly mounted on the shaft 16 and are movable thru a short arc. The shaft 16 is journaled in suitable bearings in the shell 10 and is 5 provided with a snapover spring device indicated by the numeral 17 in Figs. 1 and 2, the purpose of this spring device being to retain the shaft 16 either in the garment holding position, shown in full lines in Figs. 1 and 2, or in the detached 10 position shown by dotted lines in Fig. 2.

A pair of flexible members or stays 18 and 19, vertically disposed at each side of the buck and movable either towards or away from the sides 15 of the buck and located approximately in the same plane with the major axis of the buck shell, are controlled by means of the lever 20. The members 18 and 19 extend from the armpit to the bottom of the shirt or garment draped on the buck, as shown in Fig. 1. These members 20 18 and 19 are made of metal strips or rods of such size and form that they will readily flex and thus conform with the shape of the sides of the shirt or other garment on the buck, and, consequently, will curve inwardly, as shown in Fig. 1, when the 25 sides of the garment are so shaped.

The lever 20 is rigidly secured to a shaft 21. The shaft 21 is journalled in a bracket 22 and also in a bearing 23 (see Fig. 5), which is attached to a plate 24 mounted on the inside of 30 the buck shell 10. A ratchet wheel 25 (Fig. 1) secured to the shaft 21, and a cooperating pawl 26, pivotally mounted on the bracket 22, or other suitable device is provided for temporarily retaining the mechanism in any desired position.

35 A pinion 27 (Fig. 5) carried on the end of shaft 21, co-acts with two sector gears 28 and 29 which are rotatably mounted on the pin 30, this pin being secured to the plate, and the arrangement of these parts is such that the arms 40 31 and 32, which are rigidly attached to the sectors 28 and 29, respectively, are moved simultaneously towards each other by rotation of the lever 20 and shaft 21 in one direction, and away from each other by rotation of the shaft 21 in 45 the opposite direction, the rotation of the shaft and lever in the latter direction being made possible by disengaging the pawl 26 from the ratchet wheel 25 by actuating the pawl lever 33.

The outer ends of the arms 31 and 32 are 50 pivotally connected to the equalizers 34 and 35, respectively. The equalizer 34 is resiliently connected with the flexible member 18 by means of a pair of couplers 36 and 37, while the equalizer 35 is similarly connected resiliently with the flexible member 19 by the couplers 38 and 39 (see Fig. 5). The couplers 36, 37, 38 and 39 are identical, and each coupler comprises a bar 40, pivoted at one end to the adjacent flexible member, and rigidly secured at the other or inner end 60 to a rod 41, shouldered at the opposite end and reciprocably disposed in a tube 42, the tube 42 being pivotally connected to the end of the respective equalizer, and the tube 42 containing a compression spring 43. In passing thru the shell 65 10 of the buck, the sliding bars 40 are disposed in slotted bushings 44 which serve as bearing for the bars and also serve to retain the flexible members 18 and 19 in approximate alinement with the center of the shell 10.

70 Thus, as the shaft 21 is rotated so as to move the arms 31 and 32 and the equalizers 34 and 35 towards each other, the flexible members 18 and 19 are correspondingly moved outward from the sides of the buck, thereby stretching the sides 75 of the garment draped on the buck.

If unequal resistance to this movement should occur at the two points at which the flexible member is connected to its bars 40, the corresponding equalizer would swing on its pivot, thereby permitting the bar 40, to which the least resistance is offered, to move outwardly more rapidly until the resistance to both bars is equalized.

In actual operation when the shirt or garment has been draped on the buck as previously mentioned, and when the tape 14 has been placed in 10 holding position, the lever 20 is moved to bring the flexible members 18 and 19 against the sides of the garment. Then, when the pressing is being done, the side portions of the garment, beneath the armholes, are stretched by causing the lever 15 20 and shaft 21 to be given slight further movement. This insures the proper smoothing out of any wrinkles remaining in the body of the garment. The springs 43 prevent too great a stretching force from being exerted by the members 18 and 19 and the flexibility of these members 18 and 19 and the operation of the equalizers, permit the members 18 and 19 to adapt themselves to the proper shape of the garment sides.

During the pressing of the body of the garment 25 the sleeves are held outwardly so as not to be engaged by the pressing elements, the sleeves, cuffs and collar of the garment having been previously pressed before the garment is draped on the buck. For this purpose movable sleeve supports are provided. These movable sleeve supports comprise slidable rods 68, 69 (see Fig. 5) extending thru bushings 70 provided in the buck shell. We have found it desirable to make the rod 68 longer than the rod 69 for a reason to be 30 explained later on. The outer extremities of these rods are preferably fitted with balls 71 or furnished in any other way suitable for eliminating any unnecessary wear on the garment sleeves. The inner ends of the rods 68, 69 are pivotally 35 connected to arms 64 and 65, respectively, which are pivotally mounted in the buck shell at 66 and 67, and these arms in turn are pivotally connected to the links 62 and 63, respectively. Similarly, the links 62 and 63 connect with arms 58 and 59, 40 pivotally mounted at 60 and 61, while the other ends of the arms 58 and 59 connect to the links 56 and 57 and which in turn are pivoted to the bottom of member 54. Downward movement of member 54 causes the rods 68 and 69 to be 45 moved outward, and similarly upward movement of member 64 will cause these rods 68 and 69 to be moved inwardly.

A shaft 46, carrying the arms 47, is journalled in a casting 45, secured to the top of the buck. 50 To the bottom of these arms 47 a semi-circular band 48 is secured (see Fig. 6) which band is adapted to fit around the forward half of the neck section 12 of the buck. A rocker 49 is keyed to the shaft 46 and this rocker 49 is connected by 55 a rod 50 to a rocker arm 51 rigidly mounted on the shaft 52, the shaft 52 being also journalled in the casting 45. A lever arm 53 is attached to the outer end of shaft 52.

The member 54, previously referred to, is centrally and slidably disposed in the bottom of the casting 45. The top of this member 54 is headed and constitutes a cam follower held in constant abutment with the cam 51 by the compression spring 55. Thus movement of the lever 53 causes 70 the cam 51 to move member 54 downward which, by virtue of the toggle linkage, imparts an outward reciprocating movement to the sleeve supporting rods 68 and 69. Simultaneously with the downward movement of member 54 the cam 51, 75

thru the connecting rod 50 and the rocker 49, im-
parts partial rotation to the shaft 46, thereby
moving the band 48 into the collar clamping posi-
tion shown in Figs. 1 and 2. When the garment
5 is on the buck, the lever 53 is then moved to
clamp the collar portion in place and to extend
the sleeve supports.

It will be noticed in Fig. 5 that in the retracted
position of the sleeve supports 68 and 69, since the
10 rod 68 is longer than rod 69, the rod 68 is not
withdrawn into the buck as much as the rod 69,
but extends out part way. This has been pur-
posely arranged for we have found that the drap-
ing of the garment on the buck is facilitated—
15 assuming that the garment is pulled on the buck
from left to right as viewed in Figs. 1 and 5—if
the rod at the left is partly extended while the
other rod is in its extreme inmost position. In
this way the partly extended rod 68 serves as a
20 convenient support for the shirt or garment while
it is being slid into position on the buck. But,
which is more important, when the sleeve sup-
ports are extended, the rod 68 will extend farther
25 into the sleeve of the garment than the rod 69
and thus hold this sleeve further away from the
adjacent side of the buck. When the buck is
moved into position between the pressing jaws of
the pressing machine, it is moved sidewise, and
30 the sleeve ahead of the moving buck would nor-
mally swing back against the buck side, if the
buck is moved quickly, and might be caught be-
tween the pressing jaws. To prevent this, we have
that sleeve held further from the buck by the
rod 69.

35 This buck, as mentioned, is intended to be used
with external press elements which inclose the
buck during the pressing operation, for example,
a garment press of the enclosing concave press
jaw type, (such pressing elements, for example,
40 being shown in the co-pending application, Ser.
No. 52,366, originally filed November 30, 1935, and
renewed February 15, 1937, which issued as Patent
No. 2,126,577, dated August 9, 1938). With the
means for holding the garment on the buck which
45 we have provided and the resilient flexible means
for stretching the garment sides while the gar-
ment is so held and during the pressing opera-
tion, the entire body portion of the garment is
pressed in one operation. There is no wrinkling
50 of any part of the body portion, even tho the
shirt or garment may be form fitting. And on
the other hand, while all wrinkles are smoothed
out or stretched out, danger of damaging the gar-
ment thru the exertion of too much stretching
55 pressure is eliminated.

As previously mentioned, the shell 10 of the
buck is covered with a resilient sheath. We have
found that a sheath of vulcanized rubber of the
character now to be described is essential in se-
60 curing the most efficient results. The purpose of
the sheath on the buck is to permit strong press-
ing force to be applied when the garment is on
the buck, for example, approximately 12,000 lbs.
without, however, breaking any buttons on the
65 garment which may happen to be between the
buck and the pressing elements; and the sheath
covering must be of such nature also that, at the
places where seams or pleats occur in the gar-
ment, the single thickness of the material ad-
70 jacent the seam or pleat comprising multiple
thicknesses will also be thoroughly pressed. Thus
the sheath must be slightly compressible and dis-
placeable.

On the other hand, if the sheath yields too
75 much under the pressure exerted under pressing

elements or jaws, these pressing jaws will come
together and squeeze portions of the garment
between them. This will be understood with
reference to Fig. 7. In Fig. 7 the buck shell is in-
dicated by 10, the sheath covering by 13, the gar-
ment by 72 and the pressing jaws by 13 and 74.
We have found it highly desirable so to arrange
the buck and pressing jaws that the two jaws 13
and 74 will not come quite together at the top dur-
ing the pressing operation, but will leave a space, 10
such as shown at 75, of about $\frac{1}{8}$ of an inch be-
tween the opposed surfaces 13a and 74a. This
will cause a slight crease to be formed at the top
of the shoulders of the garment, which facilitates
the folding of the garment when it is removed 15
from the buck after the pressing operation, and
dispenses with the necessity of pressing a crease
into the shoulders separately when the garment
is to be folded. However, if the sheath on the
buck were to yield too much under the pressure 20
exerted by the pressing jaws, the two pressing
jaws 13 and 74 would come together and pinch
that portion of the shoulder of the garment in-
dicated at 76. Such pinching of the shoulder
portion of the garment between the pressing jaws 25
would tend to cut or tear the garment at that
point. Similarly, the yielding of the sheath too
much would cause undue strain at that portion
of the garment where the collar is attached, and
would result in the garment tearing at the neck- 30
band.

It is necessary, furthermore, that the sheath
on the buck should be able to stand up under
prolonged service and have sufficient "come-
back". If the sheath, on the other hand, were
of such material as would be readily fatigued, the
sheath would soon become so pressed down and
deformed as to change the relationship between
the bearing faces of the buck surface and the
pressing elements. 40

As a result of various experiments with various
kinds of materials for making said sheath cover-
ing we have found that the material which will
best meet all the requirements and give the most
satisfactory result is vulcanized rubber, prefer-
ably of approximately $\frac{1}{2}$ inch in thickness, the 45
rubber being of such composition, consistency and
resiliency, as to be capable of slight compressibil-
ity and displacement, but offering sufficient re-
sistance as a whole to the pressure of the opposed
pressing jaws to keep them spaced apart a very 50
slight distance in the manner and for the purpose
stated.

Various modifications can, of course, be made
in the details of construction of the individual
parts of our buck without departing from the
principles of our invention. It is not our inten-
tion to restrict ourselves to the specific mech-
anical means shown and described for these indi-
vidual parts, but the means described are in-
tended merely as illustrative of a preferred form
in which we have found it satisfactory to make
such parts of our buck. It is not our intention
to limit our invention otherwise than as set forth
in the claims. 65

We claim:

1. A buck for a garment press of the inclosing
concave press jaw type, comprising a buck shell
member, a sheath covering for said shell, a neck
portion, a clamping means on said neck portion,
extensible sleeve supports arranged to be movable
inwardly and outwardly with respect to said shell,
a movably mounted member for holding a gar-
ment in draped position on the buck, and flexible
side members movably mounted to stretch the 70
75

- 1 sides of a draped garment on the buck when the press jaws are in pressing position against the buck.
2. In a buck for a garment press of the inclosing concave press jaw type, a pair of extensible sleeve supports operable to place the garment sleeves out of contact with the pressing elements while the garment is being pressed on the buck, one of said supports being longer than the other
- 5 10 so as to extend further from the buck than the other at all times, means for extending and retracting said sleeve supports.
3. In a buck for a garment press of the inclosing concave press jaw type, a pair of extensible sleeve supports operable to place the garment sleeves out of contact with the pressing elements while the garment is being pressed on the buck, collar clamping means, and means for simultaneously applying said collar clamping means and 15 20 extending said sleeve supports.
4. In a buck of the character described, including a buck shell and a covering for the same, side members movable laterally from the sides of said buck for stretching the sides of a garment draped on the buck, a pair of rods supporting each of said side members and extending from the interior of said shell thru one side of the same, means operable from the outside of the buck for moving said rods outwardly and inwardly, said rods having 25 30 resilient connections whereby to prevent too great stretching pressure being exerted on said side members and thus on said garment sides.
5. In a buck of the character described, including a buck shell and a covering for the same, side members movable laterally from the sides of said buck for stretching the sides of a garment draped on the buck, said side members being flexible to conform readily to the shape of the garment at the sides, each of said side members 35 40 supported by a pair of rods extending from the interior of said shell thru one side of the same, and means for simultaneously moving said members outwardly and inwardly.
6. In a buck of the character described, a buck shell, side members movable laterally from the 45
- 1 sides of said buck for stretching the sides of a garment draped on the buck, each of said side members supported by a pair of rods extending from the interior of said shell thru one side of the same, the interior ends of each pair of said rods connected to a cross-member, each of said cross-members pivoted on an arm, means for simultaneously moving said arms and therewith said pivoted cross-members, said pairs of rods and said side members, whereby unequal resistance imposed on one-half of said side members during their outward movement, will cause such side members to tilt until the resistance is equalized.
7. The combination described by claim 6 with said means including gears in said shell, a rotatable shaft extending into said shell, and means on the outside of said shell for rotating said shaft.
8. The combination described by claim 6 with said pairs of rods connected to said cross-members by resilient spring means.
9. In a buck for a pressing machine of the inclosing press-jaw type, a shell member, said shell having shoulder supporting portions, sleeve supports extending from said shell, extensible side members laterally movable at top and bottom from the sides of said shell below said sleeve supports to stretch the sides of the garment, means for extending said side members while the press-jaws are in pressing position against the buck.
10. A buck for pressing shirts and coats in a pressing machine of the inclosing press-jaw type comprising a shell member, a resilient covering for said shell, said shell having shoulder supporting portions, sleeve supports extending from said shell, a holding means for holding a garment in draped position on said shell, extensible side members laterally movable from the sides of said shell to stretch the sides of the garment, said side members having engaging edges of flexible material to conform to both straight and curved sided garments, lever-operated means for extending said side members when the garment is held in position on the buck by said holding means.

GEORGE H. RAWLINSON.
RICHARD A. RAWLINSON.
